CLARENCE L. NORTH, OF EL PASO, TEXAS.

BALING-PRESS.

1,259,276.

Specification of Letters Patent. Patented Mar. 12, 1918.

Application filed February 9, 1915. Serial No. 7,020.

To all whom it may concern:

Be it known that I, CLARENCE L. NORTH, a citizen of the United States, and a resident of El Paso, in the county of El Paso and State of Texas, have made certain new and useful Improvements in Baling-Presses, of which the following is a specification.

My invention is an improvement in baling presses and has for its object to provide a press of the character specified, especially designed for forming hay, straw, cotton, paper, or like material into compressed, compact bales, wherein the pressure is brought about by means of a compound cam movement, requiring a minimum of power for a maximum of compression.

In the drawings:—

Figure 1 is a longitudinal vertical section of the improved press, showing the parts in one position,

Fig. 2 is a similar view showing the parts in another position,

Fig. 3 is a section on the line 3—3 of Fig. 2, looking in the direction of the arrows adjacent to the line,

Fig. 4 is a perspective view of the cam, and

Fig. 5 is a side view of the same and the plunger rod, showing the operation of the cam.

The present embodiment of the invention comprises a baling chamber 1 open at each end and having a hopper-shaped inlet 2 in its top and the baling chamber has an extension 3 at one end from each side wall. A shaft 4 is journaled transversely of the baling chamber in the extensions and in sectional bearings 5 secured to the extensions by bolts and nuts 6. It will be seen from an inspection of Fig. 3 that the extensions are channel plates, arranged with their channels outward and the sectional bearings 5 are bolted to the upper flanges of the channel plates.

A gear wheel 7 is secured to one end of the shaft 4 outside of the adjacent extension by means of a key 8 and the gear wheel 7 meshes with a pinion 9 on a driving shaft 10 also journaled transversely of the extensions and parallel with the shaft 4. The shaft 10 is adapted for connection with any suitable source of power for operating the

same, and it will be evident that when the shaft 10 is rotated the shaft 4 will be driven at a lower rate of speed.

55

The plunger 11 is secured to one end of a cylindrical plunger bar 12, and a coil spring 13 is arranged between the plunger and an angle bar 14 which connects the outer ends of the extensions. The spring acts normally to draw the plunger rearwardly. The spring 13 is connected at its ends to hooks 15 at the center of the lower end of the plunger and on the cross bar 14 respectively. The plunger rod 12 has a reduced extension 12^a at the end remote from the plunger, which passes through a stuffing box 16^a in the inner end of a cylinder 16 which is held by means of the cross bar 14 coaxial with the plunger rod.

70

The extension 12^a has a piston 19 within the cylinder and it will be noticed that the cylinder is of larger internal diameter at the end adjacent to the baling chamber than the piston. The piston is guided at the axis of the casing by guides 22, the said guides being in the shape of wings or vanes extending longitudinally of the cylinder within the same and the inner edges of the vanes are engaged by the periphery of the piston and guide the piston. Four wings or vanes are provided.

75

At the end remote from the baling chamber the cylinder is internally reduced as indicated at 17, making this portion of the interior of the cylinder of frusto-conical shape and the extreme outer end of the cylinder is again cylindrical, as indicated at 17^a. Thus the frusto-conical or tapering portion 17 connects the cylindrical portions 16 and 17^a of the cylinder.

80

Grooves 18 are arranged in the tapering portion, the said grooves extending longitudinally of the cylinder from the cylindrical portion 16 to the cylindrical portion 17^a and the grooves gradually decrease in cross section. The portion 17^a of the cylinder is of the same diameter as the piston and the grooves 18 extend to the commencement of this portion. The cylinder is adapted to hold oil and a filling nipple 20 is provided for permitting the cylinder to be filled, the nipple being normally closed by a cap 21 which is threaded thereon. On the reverse

85

90

100

stroke of the plunger, the piston 19 may move freely through the cylinder 16 until it reaches the commencement of the tapering portion 17.

- 5 The spaces between the guides 4 are of sufficient size to permit the oil to pass the piston without appreciably slowing the travel thereof. When, however, the piston strikes the commencement of the tapering 10 portion 17, the oil finds increasing difficulty in passing the piston because of the gradual contraction of the ports, that is, the grooves 18 and the piston will be checked at the commencement of the cylindrical portion 17a.
- 15 The plunger is supported intermediate its ends by a grooved roller 23, arranged on a shaft 24 extending transversely between the extensions 3 and by flanged wheels 25 which are journaled on the ends of a shaft 26, ar- 20 ranged diametrically of the plunger rod 12. Each wheel engages a track bar 27 secured to the adjacent extension 3 by means of rivets 28 and collars or arbors 29 are ar- 25 ranged on the rivets between the track bars and the extensions to space the track bars inwardly. The flanges of the wheel are on the inner sides thereof and the wheels move on the track bars. It will be noticed that the track bars extend from the inner end of 30 the packing chamber to a little beyond the shaft 4.

Three cams are mounted on the shaft 4, namely a cam 30 and a pair of cams 31. Each of the cams 30 and 31 has a hub 32 pro- 35 vided with a key way 33 for engagement by a key to key the cams to the shaft 4 and the cams are mounted on the shaft between the bearings 5. The cam 30 is adapted to move through a longitudinal slot 34 in the plun- 40 ger rod, and a roller 35 is journaled in the slot at the end adjacent to the baling chamber for engagement by the said cam. The cams 31 engage rollers 36 on the shaft 26 be- 45 fore mentioned, at opposite sides of the plunger rods, and the cams move the plunger rod and plunger in the same directions. The cams 31 are similar and in register and they are arranged on opposite sides of the cam 30.

- 50 The material to be fed is fed to the baling chamber through the hopper and a fork 37 is provided for pressing the material from the hopper into the baling chamber. The fork is supported by a pair of straight levers 55 38 and a pair of curved levers 39. A pin or rod 41 is arranged transversely of the fork at the end remote from the tines and the levers 38 are connected at one end to the ends of the rod. Each lever is pivoted at 60 its inner end to an A-shaped bracket 43, the said brackets being upright at opposite sides of the frame and connected to the inner wall of the hopper and to the adjacent extension. The levers 39 are connected to the fork in- 65 termidate the ends thereof as indicated at

40 and the ends of the levers adjacent to the fork are curved or arched as shown.

The opposite end of the lever 39 is piv- 70 otted to the joint between a pair of toggle levers 42—42a as indicated at 44. The outer end of the lever 42 is pivoted to a shaft 45 arranged transversely of the baling chamber and journaled at its ends in the A-shaped brackets, and the outer end of the member 42a of the pair is pivoted to the plunger as 75 indicated at 46, the plunger having a recess in its upper side for receiving the said end of the toggle lever.

An eye bolt 47 is connected with the shaft 45, the eye of the bolt embracing the shaft 80 and a coil spring 48 encircles the bolt be- 85 tween an adjustable stop 49 on the outer end thereof and a movable plate 50 which is en- gaged by the edge of the lever 39. The stop 49 is constituted by a washer and a nut and by means of the nut the stop may be ad- justed to regulate the tension of the spring. The operation of the device is as follows:

The shaft 10 is rotated by any suitable 90 source of power, as for instance by a motor, and as the shaft is rotated the shaft 4 will be rotated at a greatly reduced speed. The material to be baled is fed into the hopper 2 and the material is inserted when the parts are in the position of Fig. 2, that is, when 95 the plunger is at the end of its baling stroke, at which time the feeding fork 37 is lifted out of the way so that the material may be inserted through the hopper.

A shield or hood 51 is arranged above the 100 plunger and on the inner side thereof, the said shield being supported by the plunger and a pair of angle brackets 52. The angle brackets are arranged on opposite sides of the plunger rod 12 and each bracket consists 105 of two portions arranged at an acute angle with respect to each other. The longer portion is approximately horizontal inclining upwardly, however, slightly toward the vertical portion and the end of the said portion is secured to the rear or inner face of the plunger. The shield or hood is thus sup- 110 ported in an inclined position inclining upwardly toward its inner side edge and it is of such length that when the plunger is at 115 the end of its baling stroke the inner end of the shield will be behind the inner wall of the opening. The shield thus provides a cover or closure to prevent the material fall- 120 ing behind the plunger.

The material fed into the hopper rests upon the hood or shield 51 and as the plunger is moved on the reverse stroke the shield or hood moves out from beneath the mate- 125 rial and at the same time the feeding fork is swung downwardly in the position of Fig. 1 to force the material already in the hopper into the baling chamber. As the plunger moves forward on the baling stroke the feed- 130 ing fork is lifted and the shield or hood

comes beneath the lower end of the hopper to support the material until the plunger is retracted.

With the parts in the position of Fig. 1, 5 a quantity of material has just been fed into the baling chamber and the plunger is ready to start forward on its baling stroke. The cams 30 and 31 are T-shaped in cross section, in order to strengthen the same, each 10 consisting, as shown, of a cam surface and a central bracing web integral therewith and at right angles thereto. This cam surface engages the rollers 35 and 36, the cam 30 engaging the roller 35, while the cams 31 15 engage the rollers 36. As the shaft 4 is rotated with the parts in the position of Fig. 1, the operative edge of the cams 31 engage the rollers 36 at each side of the plunger rod, and as the shaft continues to 20 rotate the plunger is moved forward on its baling stroke. This forward movement continues and when the cams 31 are just about to move out of engagement with the rollers 36, the operative edge of the cam 30 comes 25 into contact with the roller 35 and supplements the action of the cams 31 to continue and complete the forward motion of the plunger.

At the end of the baling stroke the cam 30 30 passes out of engagement with the roller 35 and at this moment the cams 31 are free from the plunger rod, being above the level of the same as is also the cam 30 and there is no impediment to the rearward or reverse 35 movement of the plunger and its rod and they are drawn quickly backward by the spring 13. As the plunger and rod move rearwardly under the action of the spring a constantly increasing resistance is offered 40 to the movement of the plunger and its rod by the oil cushion, until the plunger is finally checked. Because of the fact that the slots through which the oil must escape from in front of the plunger or piston 19 45 to the rear thereof gradually decreases in capacity, there is a uniform increase in the resistance offered by the oil and the reverse movement of the plunger is checked without shock or jar.

50 At the moment the plunger is checked in its reverse movement the cams 31 again come into action to drive the plunger forwardly and the cam 30 completes the action. Every time the plunger is withdrawn the 55 feeding fork is operated to press the material out of the hopper into the baling chamber. The spring prevents injury to the feeding fork and its supporting mechanism in case there should be an obstruction in the material. When undue resistance is offered to the feeding stroke of the fork the spring 60 will yield permitting the fork to move upward and to thus avoid injury. The tension of the spring may be regulated by means of 65 the adjustable stop 49.

The plunger and rod are guided in their movement by the flange wheels 25 moving on the guide rails 27 and by the roller 23. The wheels 25 are prevented from upward movement by means of guard plates 53 which 70 are bolted to the tops of the extensions 3 and extend far enough inwardly to engage the wheels should they be lifted for any reason from the track rails. The bearings 5 have oil openings indicated at 54 for permitting 75 the shaft 4 to be lubricated. As the material is baled it is forced out of the baling chamber at the end remote from the operating mechanism into four guides 55, the said 80 guides being of angle material and engaging the corners of the bales. Any suitable mechanism may be provided for wiring or otherwise securing the baled material in bales.

It will be noted upon inspection of Fig. 85 5 that the cam 30 has a more abrupt outline than that of the cams 31. That is the cam 30 is formed on the arc of a circle of less radius than the arc of the circle upon which the cams 31 are formed. Hence the movement 90 imparted to the plunger by the cam 30 is more powerful, although the said cam 30 moves the plunger a short distance in the same length of time than do the cams 31.

Because of this arrangement the preliminary movement of the plunger is quick, while the last part of its movement is slower but more powerful. The plunger is controlled by a compound cam movement, composed of two cams of unequal radius. The 100 arrangement of the cams is such that force is applied to the plunger to cause compression during five-sixths of the rotation of the shaft 4, while the usual press applies force to the plunger during only one-half or less 105 of the movement of the operating shaft. A press of the ordinary character will require a motor capable of delivering eight to ten horse power while in the present press a motor delivering three horse power will be 110 sufficient.

It will be understood that compression is exerted during approximately five-sixths of the rotation of the shaft 4, and that any other suitable liquid or fluid may be used 115 in place of oil, as for instance air, glycerin, or any other suitable material.

I claim:

In a baling press, the combination with a baling chamber, the plunger movable longitudinally thereof, the plunger rod connected with the plunger and the spring for retracting the plunger, of power operated means for moving the plunger on the compression stroke, said means comprising a shaft journaled transversely of the chamber, the plunger having a plunger rod extending below the shaft and transversely thereof, said rod having a longitudinally extending slot, a roller journaled in the slot at the end adj- 120 125 130

cent to the plunger, a pair of rollers journaled coaxial on the plunger rod at opposite sides thereof, cams secured to the shaft and engaging the last-named rollers to initiate the movement of the plunger on the compression stroke, and a cam for engaging the first-named roller and arranged to supplement the action of the first named cam,

said cams being arranged to be free from the plunger at the end of the compression stroke to permit the spring to retract the same.

CLARENCE L. NORTH.
